ELECTRIC PLUG

Louis Ludwig, New York, N. Y.

Application July 8, 1947, Serial No. 759,651

1 Claim. (Cl. 173—361)

1

This invention relates generally to electrical attachment plugs and more particularly to the contact elements thereof.

It is known to mount a plurality of contact elements upon a resilient plug body composed of insulating material, an example of which is seen in U. S. Patent No. 2,042,580, and it is among the principal objects of the present invention to provide improvements in the contact elements of the type shown in said patent.

Another object herein lies in the provision of contact element construction in which a reliable electrical connection, of substantially low resistance is obtained between a conductor and the contact element in the plug body.

Another object herein lies in the provision of contact element construction in which a steady mechanical connection is obtained between a conductor and said contact element so that a desirable distribution of strain is produced when the conductor is subjected to pulling stresses whereby the tendency of the conductor to separate from the contact element is substantially reduced.

Another object herein lies in the provision of such construction and coordination of the parts that the conductor may be connected to the contact element in a rapid and convenient manner requiring a minimum of skill on the part of the operator and a minimum of special equipment. This results in a reduced manufacturing cost accompanied by wide distribution and use.

An important feature of the invention lies in the fact that the connection between the conductor and the contact element may be obtained by a clamping action and may be augmented by soldering in a convenient and low cost manner.

Electrical attachment plugs composed of a molded insulating material which is vulcanized or otherwise integrated with the outer insulating covering of a cord composed of one or more conductors, are well known and have proven satisfactory in a considerable number of applications. In such constructions a considerable amount of pulling strain when the cord is tugged upon by the user is carried through the outer insulating covering directly to the plug body which in turn is mechanically attached to the contact elements.

The integral molding of the cord covering and plug body is relatively expensive and prevents the small manufacturer or assembler from making connector cords of various lengths. In the present construction, the outer insulating covering need not be cemented to or molded integral with the plug body and yet the superior connection of the conductors to the contact elements enables the assembled unit to perform in many respects, substantially like an integral cord and plug body.

The present invention is concerned with a

usage similar to that in Patent No. 2,406,144 but relates to an improved construction.

These objects and other incidental ends and advantages will more fully appear in the progress of this disclosure and be pointed out in the appended claim.

In the drawings in which similar reference characters designate corresponding parts throughout the several views:

10 Fig. 1 is a front fragmentary view of a cord and plug unit embodying the invention.

Fig. 2 is an enlarged fragmentary vertical sectional view of the device shown in Fig. 1.

15 Fig. 3 is a plan view of a contact element blank in one stage of the formation thereof.

Fig. 4 is an enlarged view in perspective of a contact element in a stage following that shown in Fig. 3.

20 Fig. 5 is a view in perspective taken similarly to Fig. 4, but showing the contact element and conductor in an assembled condition.

Fig. 6 is a horizontal sectional view as seen from the plane 6—6 on Fig. 4.

25 In accordance with the invention, the assembled device or cord and plug unit is generally indicated by reference character 10, and includes broadly a cord 11 containing a plurality of conductors 12 and 13; a plug body 14; and a plurality of contact elements 15 and 16.

30 The cord 11 may be of any suitable character including the outer insulating covering 17 and the inner insulating coverings 18 and 19 which cover the individual conductors 12 and 13 respectively.

35 The plug body 14 is preferably composed of resilient insulating material such as rubber or synthetic rubber and includes a cord passage 20, hollow chambers 21 and 22, an insulating vein 23, and a bottom wall 24. The bottom wall 24 is provided with orifices or passages 25 and 26 through which the contact elements 15 and 16 downwardly project. The chambers 21 and 22 have upper walls 27 and 28 and abutment portions 29, 30, 31 and 32.

40 Since the contact elements 15 and 16 are substantially identical, except that they are oppositely arranged in position, a detailed description of one will suffice for all. As seen from Fig. 3, the blank 33 may be stamped and formed by suitably severing a continuous strip of flat stock, preferably of half hard brass so that as affected by the stamping and forming operations, the finished contact element may have the desired resiliency and conductive properties. The blank 33 has side edge portions 34, 35, 36 and 37, rounded ends 38 and 39, usual holes 40 and 41, retainer projections or tongues 42, 43, 44 and 45, a conductor entrance orifice 46, a conductor exit orifice 47 and a bending area 48 and a tunnel portion 50. The

60

tunnel portion 50 presents an external bulge 51 and an internal groove 52 (Fig. 6).

In forming the contact element 16, the blank 33 is folded at the bending area 48 through substantially 180 degrees, but the bend 53 is rounded. This forms a U-shaped body. Thus, for example, where the stock of which the blank 33 is composed is half hard brass, .030 inch thick and .252 inch wide, the inside radius of the bend 53 may be $\frac{1}{8}$ of an inch. This internal radius of the bend 53 causes the blade members 54 and 55 to converge downwardly at an acute angle so that the ends 38 and 39 contact. This distributes the strain when the blade members 54 and 55 are compressed toward each other by insertion in a receptacle (not shown) in a well known manner. The effect just described may be increased by giving the ends 38 and 39 an additional bend toward each other in the area at and below the holes 40 and 41. This tends to increase the parallelism of the inner opposed surfaces of the blade members 54 and 55 permitting a slightly greater distance for inward flexure.

Assembly of a conductor, such as the conductor 13, with the contact element 16 is preferably performed by stripping the inner insulating covering 19 from the conductor 13 for a distance slightly in excess of the distance between the orifice 46 and the orifice 47 and inserting the exposed conductor end upwardly through the orifice 46 along the groove 52 and out through the orifice 47. Following this, the bend 53 is subjected to opposed lateral pressures as is also the exposed bulge 51. This pressure is sufficient to change the bend 53 from the rounded form shown in Fig. 4 to a relatively acute form shown in Fig. 5. The pressure which serves to make the bend 53 more acute is confined closely to the apex of the bend so that the bowed effect seen in Fig. 2 and Fig. 5 is not lost. This assures that the blade elements 54 and 55 shall remain in a spaced condition allowing for inward flexure when the contact elements are engaged in a well known receptacle or socket (not shown). Pressure inwardly of the contact element 16 is applied also on the bulge 51 which causes the tunnel portion 50 to flatten slightly or increase its cross sectional radius of curvature. The amount of deformation caused by the last mentioned pressure will depend on a number of factors including the value of the pressure, the formability of the stock of which the contact element 16 is composed, the effective bulk of the uninsulated end 56 of the conductor 13. This effective bulk will be affected by such considerations as whether or not the conductor 13 is strained or solid, and its gauge.

With the parts assembled as shown in Fig. 5, considerable mechanical pressure is exerted upon the uninsulated terminal 46. With certain gauges of conductor, their predetermined thicknesses of inner insulating covering, a portion of the covering 19 may be frictionally retained within the tunnel member or portion 50. The substantially 180 degree bend 57 in the conductor 13 and covering 19 produces a snubbing effect which absorbs tension upon the conductor 13 upwardly as viewed in Fig. 5, retarding the transmission of such tension to the area between the upper ends of the blade members 54 and 55 where the electrical contact is being obtained.

Where it is desired to increase the conductivity of the electrical joint between the uninsulated end 56 and the contact element 16, particularly over longer periods of time, and where a surface oxidation or corrosion is to be prevented, the

whole upper end extending preferably as far as the point 58 of the assembly of Fig. 5 may be dipped in flux and molten solder. During such a dipping the conductor 19, of course, is rotated through approximately 180 degrees so that it lies along the outer surface of the blade member 54.

After assembly and fabrication of the contact elements or contact element units including a conductor and contact element in combination, they may be assembled within the plugged body 14 in a well known manner. This may be done for example, by temporarily distorting the plug body and drawing the parts into the body with suitable tools. As seen in Fig. 2, the retainer projections engage correspondingly positioned abutment portions while the conductor terminals 60 and 61 embed themselves in the upper walls 27 and 28 of the hollow chambers 21 and 22. This serves to further anchor the conductor with respect to the plug body, as well as to further anchor the contact elements with respect to the plug body for greater utility and durability. It may thus be seen that I have disclosed a novel and useful electrical attachment plug construction which affords desirable electrical and mechanical characteristics by which by virtue of the simplicity thereof may be manufactured in large scale with substantially no increase over prior constructions of lesser effectiveness.

I wish it to be understood that I do not desire to be limited to the exact details of construction shown and described, for obvious modifications will occur to a person skilled in the art.

I claim:

33. In a plug, a body having a cord passage at one face leading to a central cavity with prong passages leading through another face of the body, and prongs extending through said passages, each of the prongs being formed of a strip of resilient metal bent upon itself to form a bent portion and opposing leg portions, one of the leg portions having an entrance wire orifice, the bent portion of the prong having an exit wire orifice, a groove portion in the one leg leading from one orifice to the other, a retainer projection on at least one of the leg portions, said leg portions upon being restricted in the prong passage serving to maintain a relatively acute bend in the bent portion to flatten the exit orifice and to bind a wire therein which may be extended into the entrance orifice and along the groove and through the exit orifice in the bent portion whereby the wire is resiliently engaged by the wall of the groove and the opposed leg portion, the opposed leg portions being resiliently spaced adjacent the outer end of the prong passage and engaging with one another at their outer ends.

LOUIS LUDWIG.
